FIRE-RESISTING SHUTTER OR DOOR.

1,204,738.

Specification of Letters Patent. Patented Nov. 14, 1916.

Application filed January 9, 1914. Serial No. 811,174.

To all whom it may concern:

Be it known that we, WILLIAM M. BRUNST and EDWARD H. MCLOUD, citizens of the United States, residing at Columbus, in the 5 county of Franklin and State of Ohio, have invented a certain new and useful Improvement in Fire-Resisting Shutters or Doors, of which the following is a specification.

The object of this invention is to provide 10 improved means whereby the curtain of such a shutter or door is suspended and held locked from further movement after it has closed.

A further object of the invention is to 15 improve the counterbalancing of the curtain and provide a large starting movement to effect the automatic closing of such shutters or doors.

Other objects will appear from the following description.

The invention is embodied in the example herein shown and described, the features of novelty being pointed out in the claims.

In the accompanying drawings—Figure 1 25 is a front elevation showing the barrel or shutter supporting member in longitudinal section. Fig. 2 is an end view showing the controlling mechanism. Fig. 3 is mainly a vertical section on the line $x-x$ Fig. 2. Fig. 30 4 is a section on the line $y-y$ Fig. 3 to show the volute groove on the outer side of the wheel or member here depicted. Fig. 5 is a section on the line $z-z$ Fig. 3 to show the volute groove on the inner side of the 35 said wheel or member.

In the views 10 designates the barrel or drum to which the flexible shutter or curtain 10^a is secured in the usual or any suitable manner. Said barrel or drum at its 40 left hand end is supported upon a shaft 11 which in turn is supported in a bracket 12. The shaft 11 has fixed to its outer end beyond the bracket a retaining wheel 13 having around its rim a number of holes 13^a 45 into any one of which a pin 14 in a lug on the bracket can be inserted to secure the shaft from rotation. Within the barrel is a spring 15 secured at one end to a collar 16, pinned to the shaft, and having its other 50 end attached to a plug 17 that in turn is secured to the drum and rotates on the shaft 11. The spring or tension member 15 is for the purpose of counterbalancing the shutter or curtain to make it easy of operation,

55 manual or otherwise and to hold the same suspended at the point to which it is raised or lowered. The other end of the barrel is supported upon a tubular shaft or extension 18 of the plug member 18^a. This tubular shaft 18 is shown as supported on roller 60 bearings in the end bracket 12^a, the end of the shaft protruding somewhat beyond the outer face of the bracket. Just beyond this bracket and mounted loosely on the shaft 18 is a wheel 19 having a radial slot 19^a and 65 notches 19^b at frequent intervals in its rim. A pin 23 in the bracket 12^a locks the wheel 19 in any position to which it is adjusted. Keyed on said shaft 18 adjacent said wheel 19 is a wheel 20 that has in one face a volute groove 20^a and in the opposite face a volute groove 20^b. The direction of each 70 of these volute grooves starting from its inner end is right hand. Loose on the protruding end of a shaft 21 that extends from 75 the interior of the barrel through the tubular shaft and adjacent the wheel 20 is a wheel 22 having a radial slot 22^a and rim spurs 22^b. Secured on the extremity of said shaft 21 is a ratchet wheel 24 having sockets 80 24^a in its rim into which a bar (not shown) can be inserted for turning said ratchet wheel and the shaft 21 as hereinafter explained. A pawl 25 on the wheel 22 engages the ratchet when turned to the left but when 85 the ratchet has been turned as far as desired a bolt 22^c on the wheel 22 is engaged with the proper socket 24^a of the ratchet to lock it.

The inner end of the shaft 21 is supported in the axial opening of a collar 26 pinned to the inner end of the shaft 11 so that the collar and shaft 11 can turn with reference to the shaft 21 or the shaft 21 turned in the collar, and connected with 95 a collar 27 pinned on said shaft 21 and the collar 26, is a coil spring 28, adapted when placed under tension to act on the drum counter to the action of the spring 15. The spring 28 when the shaft 11 is held as by the 100 pawl 25 acts on the barrel through the ratchet wheel 24 and pawl 25, the wheel 20 and the connection between the said parts as hereinafter explained.

In the volute groove which is in the face 105 of the wheel 20 next the wheel 19 is a traveler consisting of a curved elongated base portion 29 fitting in the volute groove and

a pin 29^a to project into the radial slot 19^a so that if the wheel 20 be turned the pin shall travel in one direction or the other according to the direction in which the 5 wheel is turned until the traveler arrives at the end of the groove or at the end of the slot as the construction may be. The volute groove in the opposite face of the wheel 20 also has a traveler or lug consisting of a 10 base 30 and pin 30^a to project into the radial slot 22^a of the spur wheel 22 and the operation of this traveler is the same as that first described but when the wheel 20 is turned in one direction the two travelers 15 move in directions opposed to each other.

The wheel 22 and therefore the tension member 28 is latched from operation on the barrel by means of a latch lever 31 fulcrumed 31^a on the side of the bracket 12^a 20 which engages one of the spurs 22^b and itself is held up in latching position by means of another lever 32 pivoted on an ear 32^a the lever 32 being supported by a wire 33 attached to a fixed point and containing a 25 link 34 fusible upon a dangerous rise of temperature such as occasioned by fire near the shutter. Upon the occurrence of such a fire the levers 32 and 31 are liberated and the spring 28 operates through the ratchet 30 24, pawl 25, wheel 22 and traveler 30—30^a on the drum to unroll or lower the curtain. The traveler 30—30^a is arranged so that it lies at or near the outer terminus of the volute groove when the curtain is in its 35 completely raised position, but if the curtain be liberated, as by the occurrence of fire, this traveler is slid or driven to the terminal wall of said groove by the spring 28 after which the tension of the spring is exerted on the 40 barrel to drive down the curtain.

When the ordinary curtain now on the market is held suspended by a resistance of the counterbalance spring or springs of tempered steel the temper of the springs may be 45 destroyed by the fire thereby rendering them ineffective to resist downward movement of the curtain. In such case the curtain may overhaul the barrel, stack up in the grooves and bulge out the grooves forming openings 50 through which fire can pass. In the present construction, when the curtain is properly down, the traveler 29—29^a locks the barrel to the wheel 19, the latter being fixed to the end bracket 12^a by the pin 23 as before described. In the present construction 55 therefore the curtain is supported by the end bracket and prevented from unduly descending in the channels. To secure this effect, the curtain when the structure is 60 originally installed, is first pulled down as far as it is intended it shall ever go and the wheel 22 turned from left to right until the traveler 29 brings up against the inner terminal wall of the volute groove after 65 which the pin 23 is inserted in the notch

of the periphery of the wheel 19 to lock the latter from rotation with reference to the end bracket. As the curtain is raised and lowered in normal operation the traveler 29—29^a is merely carried outward or 70 inward in the groove 19^a by the action of the volute groove.

The construction as shown and described is susceptible of some modifications without departing from the gist of the invention 75 as claimed.

What we claim is:

1. In a fire resisting shutter or door, the combination of a curtain, a winding barrel or drum for the curtain, a tension member for the barrel or drum, a volute member and a guiding member, one of said members adapted to be actuated by and upon the release of the tension member, a lug engaging both the volute and guiding members, said lug adapted to limit the movement of one of said members with reference to the other, and thermally controlled means for restraining the release of the tension member. 85

2. In a fire resisting shutter or door, the combination of a curtain, a winding barrel or drum for the curtain, and locking means to limit the unwinding movement of the barrel consisting of a lug, a fixed guiding member therefor and a volute member operated 95 by the barrel or drum to actuate the lug to move it into position to lock the volute member and lug-guiding member together.

3. In a fire resisting shutter or door, the combination of a curtain, a winding barrel or drum therefor, and locking means to limit the unwinding movement of the barrel or drum and curtain consisting of a lug, an adjustable guiding member therefor and means for fixing the same in adjusted position, and 100 a volute member operated by the barrel or drum to actuate the lug to move it into position to lock the volute member and lug-guiding member together. 105

4. In a fire resisting shutter or door, the combination of a curtain, a winding barrel or drum therefor, and locking means to limit the unwinding movement of the barrel or drum and curtain consisting of a lug, a slotted member for guiding the same and a volute member operated by the barrel or drum to actuate the lug to move it into position to lock the volute member and the slotted guiding member together. 110

5. In a fire resisting shutter or door, the combination of a curtain, a winding barrel or drum therefor, a tension member, a volute member actuated by the barrel or drum, a lug, a guiding member therefor, said lug being actuated by the volute member to lock 125 the guiding member and volute member together, and thermally controlled means for latching the guiding member.

6. In a fire resisting shutter or drum, the combination of a curtain, a winding barrel 130

or drum therefor, a tension member, a volute member actuated by the barrel or drum, a lug, a guiding member therefor, said lug being actuated by the volute member to lock the guiding member and volute member together, means for regulating the stress of the tension member on the guiding member and thermally controlled means latching the guiding member. 5

10 7. In a fire resisting shutter or door, the combination of a curtain, a winding barrel or drum therefor, a tension member to act on the barrel including a shaft projecting beyond the barrel, a volute member actuated by the barrel or drum, a lug, a guiding member therefor, said lug being actuated by the volute member to lock the guiding member and volute member together, means on the tension member shaft and guiding member 15 for regulating the tension member, and thermally controlled means for latching the guiding member. 20

8. In a fire resisting shutter or door, the combination of a curtain, a winding barrel or drum for the curtain, locking means to limit the unwinding movement of the barrel consisting of a lug, a fixed guiding member therefor, a volute member operated by the barrel or drum to actuate the lug to move it 25 into position to lock the volute member and guiding member together when the curtain is unwound, a tension member, a second volute member actuated by the barrel or drum, a second lug, a guiding member therefor actuated on by the tension member, said last named lug being actuated by the last named volute member to lock said last named guiding member and volute member together, and thermally controlled means latching said 30 40 last named guiding member. 45

9. In a fire resisting shutter or door, the combination of a curtain, a winding barrel or drum therefor, locking means to limit the unwinding movement of the barrel, a counterbalancing tension member for the normal operation of the curtain, a second tension 50 member to act counter to the first mentioned tension member, a volute member actuated by the barrel or drum, a lug, a guiding member therefor actuated by the second named 55 tension member, said lug being actuated by the volute member to lock the guiding member and volute member together, and thermally controlled means for latching the guiding member from actuation. 55

10 10. In a fire resisting shutter or door, the combination of a curtain, a winding barrel or drum for the curtain, a tension member for the barrel, a volute member and a guiding member, one of said members being operably connected with the drum and the other having means for adjusting and fixing it in position, a lug engaging both the guiding member and the volute member, said lug adapted to limit the movement of one of 60 said members with reference to the other. 65

11. In a fire resisting shutter or door, the combination of a curtain, a winding drum or barrel for the curtain, a releasable tension member for the barrel, a volute member and a guiding member, one of said members being operably connected with the barrel and the other having means for adjusting and fixing it in position, a lug engaging both the guiding member and the volute member, said 70 lug adapted to limit the unwinding movement of the barrel, a second volute and guiding member, one of said members being actuated by the tension member and having means for adjusting and fixing it in position, a lug engaging both of said last mentioned volute and guiding members, said lug adapted to limit the unwinding of said tension member, and thermally controlled means 75 for restraining the release of said tension 80 member. 85
